UNITED STATES PATENT OFFICE

112,366

DESIGN FOR AN AUTOMOBILE SIGNAL LAMP

Loomis N. Franklin, Evansville, Ind.

Application April 22, 1938, Serial No. 76,705

Term of patent 7 years

To all whom it may concern:

Be it known that I, Loomis N. Franklin, a citizen of the United States of America, residing at Evansville, county of Vanderburgh, and State of Indiana, have invented a new, original, and ornamental Design for an Automobile Signal Lamp, of which the following is a specification, reference being had to the accompanying drawing, wherein:

Figure 1 is a front elevation of an automobile signal lamp, showing my new design.

Figure 2 is a bottom plan view.

Figure 3 is an end view.

I claim:

The ornamental design for an automobile signal lamp, as shown.

L. N. FRANKLIN.
